US0D1041087S

(12) **United States Design Patent** (10) Patent No.: **US D1,041,087 S**
(45) Date of Patent: ** Sep. 3, 2024

(54) **PROTECTIVE MASK**

(71) Applicant: **KORE OUTDOOR (US), INC.**, Fort Wayne, IN (US)

(72) Inventors: **Simon Benjamin Stevens**, Barnsboro, NJ (US); **Bryan Stowe**, Sewell, NJ (US)

(73) Assignee: **KORE OUTDOOR (US), INC.**, Fort Wayne, IN (US)

(**) Term: **15 Years**

(21) Appl. No.: **29/756,131**

(22) Filed: **Oct. 26, 2020**

Related U.S. Application Data

(60) Continuation of application No. 29/623,659, filed on Oct. 26, 2017, now Pat. No. Des. 900,405, which is a continuation of application No. 29/488,569, filed on Apr. 21, 2014, now Pat. No. Des. 801,589, which is a continuation-in-part of application No. 29/370,432, filed on Jun. 14, 2010, now Pat. No. Des. 703,388, which is a continuation of application No. 29/327,424, filed on Nov. 5, 2008, now abandoned, which is a division of application No. 29/253,707, filed on Feb. 10, 2006, now Pat. No. Des. 589,211.

(57) **CLAIM**

The ornamental design for a protective mask, as shown and described.

DESCRIPTION

FIG. 1 is a front perspective view of an embodiment of a protective mask according to our invention;

FIG. 2 is a front elevational view of the design shown in FIG. 1;

FIG. 3 is a right side elevational view of the design shown in FIG. 1, the left side being a mirror image thereof;

FIG. 4 is a top plan view of the design shown in FIG. 1; and,

FIG. 5 is a bottom view of the design shown in FIG. 1.

All broken lines appearing in the drawings form no part of the claimed design.

1 Claim, 4 Drawing Sheets
